UNITED STATES PATENT OFFICE

2,593,489

PRINTING TELEGRAPH RECEIVER

Reginald Dennis Salmon and Frederick James Leslie Turner, Croydon, England, assignors to Creed and Company Limited, Croydon, Surrey, England

Application July 7, 1948, Serial No. 37,378
In Great Britain July 25, 1947

1 Claim. (Cl. 178—27)

1

This invention relates to printing telegraph receivers and more particularly to receivers in which storage members are set in accordance with the code elements of the received signal combination and in which the storage members are afterwards caused to act upon translator mechanism whereby a letter or character is printed, or such other function is performed by the machine, as corresponds to the particular signal combination received.

The present invention relates to the selecting and storage mechanism only.

In British Patent Specification No. 600,297 it is explained that the degree of tolerance for distorted signals which a printing telegraph receiver can develop depends largely on the moment of inertia of certain moving parts one of which is the armature of the receiving magnet. The armature normally occupies one of two positions, usually referred to as "mark" and "space" and is retained in either one or other position according as to whether the current condition in the winding of the magnet represents a mark or a space signal element. Received signal combinations corresponding to individual letters, characters or functions are represented by a predetermined succession of "marks" and/or "spaces."

The smaller the moment of inertia of the armature system the more rapidly the armature will travel from one position to the other when a change occurs in the current in the winding, and the more tolerance is permissible in the timing of the received signal impulses.

In the type of printing receiver under consideration it is necessary that a succession of storage members should be set into positions corresponding to "mark" or "space" determined by successive positions of the receiving relay armature. Printing telegraph systems usually involve the use of a code in which each character or function is represented by a fixed number of signal impulses, commonly five, each of which may be a mark or a space. Thus, for a five unit code there must be five storage members and the armature must operate so as to set them one after another. As set forth in said British patent one well-known method of accomplishing this involves the use of a member mounted on the armature of sufficient size to cover the positions of all the storage members, means being provided whereby an intermediate striking pin is brought into position between the armature and each storage member in turn. Another well known solution involves the swinging of the stor-

age members one at a time into the proximity of the armature member, this again necessitating an armature member of sufficient size to cover the positions of all the storage members.

5 In said British patent there is disclosed an improved means of setting the storage members by traversing a frame carrying said members, past the armature in such a way that one storage member is presented to the armature at a time and is then set in accordance with the positions taken up by the armature under the control of the next signal element received. It is therefore only necessary for the armature member to be large enough to act on one storage member at a time and thus the moment of inertia of the armature system can be reduced.

10 According to this last method when all the storage members have been set the indications have to be transferred to the translator mechanism after which the frame carrying the storage members has to be restored to its original position, and the storage members reset to normal before the first storage member can be presented to the armature for the reception of the 15 first element of the next signal.

20 The object of the present invention is to provide improved means for setting the storage members in accordance with the received signal elements which will avoid the necessity of traversing the storage members while yet permitting the use of an armature member of minimum size, and to enable the maximum possible overlap in the timing of the several operations to be obtained. The storage members may be of the same 25 general design as those disclosed in the above-mentioned application, but they are not mounted in a traversing frame.

30 According to one feature of the present invention, a signal selector and storage mechanism for a printing telegraph receiver in which a striking member is caused to set a plurality of storage members one at a time, each such member being selectively set in accordance with the position of an armature member carrying said striking member, is characterised in this, that the striking member is of dimension no larger than would be necessary to coact with one storage member only but is caused to coact with each storage member in turn by acting upon an intermediate 35 member spanning the positions of all the said storage members, and that means is provided for causing said intermediate member to act selectively upon said storage member in turn. This intermediate member may consist of a light 40 frame pivotally mounted on a fixed rod and able

2

to rotate through a limited arc about the rod. The frame is struck and rotated by the striking member controlled by the relay armature when a signal element requiring the setting of a storage member is received and the movement of the frame is caused to set the storage member by means which will later be described.

According to one embodiment of the invention, the setting member is a pin slidably mounted in a rod and with its axis at right angles to that of the rod. The rod is traversed in such a way that the pin is presented to each of the storage members in turn and the pin is struck by the light frame when it is rotated by the striking movement of the armature member. The pin accordingly sets the appropriate storage member.

According to a preferred embodiment of the invention however, the light frame itself is not only rotatable about the fixed rod on which it is mounted, but is also able to slide along the rod. The frame in this case is provided with a projecting arm which constitutes the setting member and this projecting arm is presented to the storage members one at a time successively and sets the storage members when the frame is rotated by the striking action of the armature member. The light frame is traversed by the operation of a cam on one of the rotating shafts.

According to another feature of the invention we provide a signal selector and storage mechanism for a printing telegraph receiver comprising an electromagnet having an armature, a plurality of storage members, one for each element of the code, a striking member of dimensions no larger than would be necessary to coact with one storage member only, means for moving said striking member in one path under control of the response of the armature to received signals, means for reciprocating the said striking member relatively to said armature in another path in respect of each code element of a received signal, a setting member traversable with respect to said striking member and said storage members to cause the last mentioned movements of the said striking member to selectively set said storage members in turn.

The invention will be better understood from the following description of one embodiment taken in conjunction with the accompanying drawings in which:

Fig. 1 is a representation of the receiving magnet and armature and the striking mechanism, and

Fig. 2 is a representation of the mechanism whereby the movements of the striking member are caused to set the storage members.

Fig. 3 shows the cam contours and timing involved in the carrying out of the operations described.

In Figure 1 there is shown the receiving magnet 1 provided with an armature 2 rigidly attached to a spindle 3 carried in fixed bearings (not shown). The tension of spring 4 operates to draw the armature away from the magnet, but is not sufficient to overcome the pull when the magnet is energised by a signalling current. An arm 5 is rotatably mounted on spindle 3, and the end 6 of the arm is bent at right angles and provided with a slot through which the striking member or "striker" 7 passes. The striker can be better seen in Fig. 2, and its operation will be described later.

A lever 14 known as the armature re-setting lever is rigidly mounted on spindle 3 and one end 15 of this lever is actuated by a cam on shaft 13.

It follows that every time a crest of the cam raises the end 15 of the lever 14 spindle 3 is rotated through a small angle and the armature 2 will be brought into close proximity to the pole piece of electro-magnet 1. The far end of lever 14 is bent over at right angles to form an extension 17 which lies under a projection 18 on the arm 5. When arm 5 is held in its upper position by means to be described shortly, the end 15 of lever 14 will continue to follow the cam contour on shaft 13 owing to the action of the torsion spring 16 interconnecting arm 5 and lever 14. When, on the other hand, arm 5 is held in its lower position by the means to be described (which occurs when the armature 2 is maintained close to the pole piece of electromagnet 1 by current in the magnet winding) extension 17 of lever 14 is held down by projection 18 on arm 5 and no longer follows the cam contour on shaft 13.

Another lever 19, known as the "chopper lever," is mounted on a pivot 20 and one end 21 of this lever is caused to follow continuously a cam on the selector shaft 13 by the action of spring 22. The other end of lever 19 has a turned over end 23 which co-operates with a second projection 24 on arm 5. Each time a crest of the cam on shaft 13 raises the end 21 of lever 19, the end 23 of the lever 19 is moved into a position which permits projection 24 on arm 5 to move up or down without coming into contact with the turned over end 23 of lever 19. The cam contours operating the armature re-setting lever 14 and the chopper lever 19 are so shaped and positioned that lever 19 is held in the position which permits arm 5 to move up or down during the period in which the armature 2 is brought close to the pole piece of magnet 1 by the action of the armature re-setting lever 14 and is still held in this position for a short period after the end 15 of lever 14 has been released by the cam, during which period the armature 2 is either retained close to the pole piece of the magnet 1 or allowed to drop away, according as to whether the magnet is energised or not by the signal being received. During this short period the end 21 of lever 19 is released and end 23 of the lever is adapted to be positioned either under or over end 24 and thus lock arm 5 either in its upper or lower position according to the nature of the signal element being received.

It can be seen therefore that the arm 5 is actually moved up and down by the cam driven action of the re-setting lever 14 acting through torsion spring 16, but the movements of arm 5 may be delayed by the action of the chopper lever 19, and arm 5 will be held down until released by the lever 19 if the signal element received is one which energises the receiving magnet 1. As will be explained later, the armature re-setting lever 14 is operated six times in each revolution of the selector shaft 13 since it has to cater for the stop signal, but the chopper lever 19 only operates five times per shaft revolution since the locking of the arm 5 is only required during the receipt of the five elements of a code combination.

As has been explained above, the turned-over end 6 of arm 5 is provided with a slot through which striker 7 projects. This can be better seen in Fig. 2, to which reference should now be made. A striker lever 8 is rotatably mounted on a fixed pivot at 9 and the end of the striker 7 away from end 6 of the arm 5 is attached to one end of striker lever 8 by means of a pivot 10. The other end 11 of striker lever 8 is pressed by

the spring 12 against a cam carried on the selector shaft 13. Five times in each revolution of the selector shaft 13 the cam activates striker lever 8 and drives the striker 7 outwards through the slot in the end 6 of arm 5; the striker being withdrawn by spring 12 as soon as the end 11 of striker lever 8 is dropped by the cam.

The striker lever 8 is operated by the cam while the arm 5 is held locked by the chopper lever 19 and the striker 7 is struck outwards through the slot in the turned over end 6 of arm 5, being immediately afterwards withdrawn to its normal position by the action of spring 12 as explained above. It can now be seen that the purpose of the chopper lever 19 (Fig. 1) is to ensure that the striker 7 is held correctly in the position corresponding to the last signal element received until the indication has been transferred to a storage member in a manner which will now be described.

In Figure 2 the armature resetting mechanism and the chopper mechanism have been omitted for the sake of clearness.

In the figure there are shown storage members 25.

These storage members, of which there is one for each signal element of the code (i. e. five in the case of five unit code, only three are shown in the figure) are rotatably mounted on a fixed pivot pin 26 separated from one another by friction washers (not shown) rigidly fixed to the pin and pressed together by a spring (not shown). The details and the action of the storage members are described in said British patent. According to the present invention however the pin 26 carrying the storage members is fixed and there is no traversing movement of the assembly of the storage members along the axis of the pin. A light frame 27 is suspended from a fixed rod 28 at points 29 and this light frame is traversed along rod 28 by the action of lever 30 mounted on a fixed pivot 31, one end of lever 30 engaging the frame 27 near one of the suspension points 29, while the other end 32 is held against one end 33 of another lever 34 by the action of spring 35. Lever 34 is mounted on a fixed pivot 36 and its other end 37 is held against a cam mounted on the selector shaft 13 by means of spring 38. The shape of the cam co-operating with the end 37 of lever 34 is such that as the shaft 13 rotates the frame 27 is moved axially along shaft 28 from its extreme right-hand position as shown in the figure to its extreme left-hand position and is then immediately brought back to its extreme right hand position by the action of spring 35, this complete cycle occurring once for each revolution of shaft 13. It is to be noted that spring 35 acts in opposition to spring 38. The tensions of these springs are so adjusted that spring 35 is not powerful enough to withdraw the end 37 of lever 34 from contact with the cam on selector shaft 13. Thus the light frame 27 is traversed in one direction by the action of spring 38 and in the return direction by spring 35 but if owing to any mechanical defect the movement of frame 27 is impeded, no positive force exerted by the cam will be applied to the frame and cause mechanical damage. If frame 27 becomes accidentally held in some intermediate position a gap will appear between the co-operating ends 32 and 33 of levers 30 and 34 respectively or the end 37 of lever 34 will remain out of contact with the cam. Frame 27 is provided with a projection 39 and as the frame is traversed this projection is brought in line in

turn with the upper arms of each of the storage members 25. In the storage member shown in the right, the upper arm 40 is designated. The lower edge 41 of frame 27 is so positioned that it is directly opposite the end of the striker 7 when the armature of the receiving magnet is in one of its two operative positions and if the striker lever 8 is operated while the striker 7 is in this position the lower edge 41 of frame 27 will be struck and the frame will be rotated through a limited angle around rod 28. Projection 39 will therefore strike the arm 40 of one of the storage members 25 and will rotate that storage member through an angle causing the long arm 42 of the storage member to be moved downwards. If the striker 7 is in its other possible position at the moment when striker lever 8 is operated the striker, although driven forward, will not strike the edge 41 of frame 27 and whichever storage member 25 is opposite projection 39 of frame 27 will not be struck and will remain in its normal position. Frame 27 is restored to its normal position immediately after each occasion upon which it is actuated by the striker 7 by spring 43 acting on a restoring member 44 rotatably mounted on rod 28 at 45. The limit of travel of frame 27 as it returns to its normal position is determined by a fixed bar 46.

Thus, after five successive elements forming a complete code combination have been received, some of the storage members 25 will usually have been struck and others not, those which have been struck will have their long arms 42 depressed. When the five elements forming one combination have been received the traversing mechanism consisting of levers 30 and 34 restores the frame to its original position ready for the next signal.

Meanwhile the mechanism for transferring the stored signal combination to the translating mechanism comes into operation. This is substantially as described in said British patent. After the last element of any code combination has been received, the shaft 48, on which the two arms 47 carrying the pivot pin 26 are rigidly fixed, is rotated through a limited angle. Only the further arm 47 is shown in Fig. 2, the corresponding second arm 47 supports the nearer end of pivot 26 and is omitted to simplify the drawing. This rotation of shaft 48 moves the storage members 25 away from the striking frame 27 and towards the bell crank levers 49 which are themselves engaged with the vertical rods 50 (only one of which is shown) which actuate the translator mechanism as described in said British patent.

Shaft 48 is actuated by means of a member 51 rigidly fixed thereto and co-operating with a cam carried on the translator shaft 52 which moves the forked ends 53, 54 of member 51. When end 60 53 is raised, the five storage members 25 are moved towards the bell cranks 49 and the long arm 42 of each storage member engages either the upper or the lower of the corresponding pair of bell cranks 49 thus moving the associated vertical rod 50 into its limiting upper position or into its limiting lower position. As soon as the signal combination stored by the five storage members has been transferred to the five vertical rods, the forked end 54 of members 51 is actuated by the cam on the translator shaft 48 and the arm 47, carrying the pin 26 on which the storage members are mounted, is brought back to its normal position. Immediately after the storage members have been brought back to their normal position they are reset to be ready for the next

signal combination by means now to be described.

A frame 55 is rotatably mounted on shaft 48 and has an arm 55 which continuously follows a cam on the translator shaft 52 in consequence of the tension of spring 57. Once in each revolution of the translator shaft 52, just after the storage members have been brought back to their normal position, a cam on the shaft 52 moves the arm 56 of frame 55 and rotates the frame 55 through a limited angle in a direction away from the frame 27. Frame 55 is thereby pressed against the lower extending arms of the storage members 25 and any such members which were in the operated position, i. e., with their long arms depressed, are restored to their normal positions ready to be set by the next stroke of the striker 7 acting through projection 39 as has already been described.

From the foregoing description it can be seen that the operations involved from the moment of the commencement of the reception of any incoming signal combination till the complete combination has been transferred to the translating mechanism are divided into two distinct stages. Thus, the incoming signals actuate the receiving magnet armature and bring the striker 7 into position either to strike or miss the striking frame 27. The striking frame 27 is traversed while the signal combination is being received and the projection 39 thereon is presented to each storage member in turn. The end of the first stage can be considered to be the moment when the last signal element has been received and the last storage member set. As soon as the last signal element has been received and the last storage member set, the striking frame 27 may be traversed back to its initial position, this movement taking place at the same time as the assembly of storage members is being rocked forward to transfer the stored signal to the vertical rods 50. The fact that some of the restoring movements take place before the transfer of the signal combination to the translator mechanism is completed, leads to a valuable saving of time, permitting of greater reliability in operation and enabling operating speeds higher than previously obtainable.

As will have been realised from the foregoing description, the successful operation of the selector and storage mechanism is dependent on the correct timing of the successive movements by means of the various cams referred to and this will now be explained in greater detail.

Fig. 3 is a diagram which shows the contours and timing of the various cams and the operation of the mechanism described above can be readily understood by following the movements of the various parts.

In the figure, line "A" shows two complete received five element code combinations each preceded by a start element (space) and followed with a stop element (mark). Thus, the first complete signal is represented by a start element (15 milliseconds) followed by mark, space, mark, space, mark each of about 15 milliseconds duration, and a stop element (shown as about 7½ milliseconds). At this point the receiver would be stopped and, as shown, immediately restarted by the next start element the following elements being mark, space, mark, space, space, stop.

Line "B" shows the cam contour operating the

7 armature resetting lever 14 which operates six times for each signal combination.

This brings the armature 2 up against the receiving magnet 1 after the commencement of each received element and then releases it; if the magnet is energised the armature remains held by the magnet, if the element is of the other kind the armature is drawn away from the magnet as soon as the resetting lever 14 is released. It will be noticed that the resetting lever 14 is not operated for the start element, indeed it could not be for the cam shaft 13 is at rest when this element is received. The normal rest condition of the transmission circuit is with mark current flowing and the connections are so arranged that the magnet 1 continues to be energised during the rest condition. Thus, the armature is held against the magnet after the stop element (mark) until the next start element (space) releases it, whereupon it starts up the receiving mechanism. The resetting lever 14 is released, as stated above, while the element is still being received and the armature 2 is then either held against the magnet 1 or released according as to whether the magnet is energised or not. Shortly after the resetting lever 14 is released, the chopper lever 19 is operated by the cam contour shown in line "C" of the figure. This lever 19 locks the cam carrying the striker 7 in the position corresponding to the signal being received while the cam contour shown in line "D" operates to drive the striker forward and, as described above, to set the appropriate storage member 25. It will be noticed that the next movement of the resetting lever 14 (line B) commences before the chopper lever 19 is released. This movement of the resetting lever 14 commences to bring the armature 2 towards the receiving magnet 1 and the arm 5 carrying the striker 7 follows the armature under the action of the torsion spring 16 (Fig. 1) the moment the chopper lever 19 releases the arm 5.

Line "E" of Fig. 3 shows the contour of the cam which traverses the light frame 27 (Fig. 2) which transfers the indications given by the striker 7 to the appropriate storage members 25. The return traversing movement commences at the end of the fifth movement of the striker 7 and is completed during the next following start element when the cam shaft 13 is again in rotation after its pause.

Line "F" shows the cam on the selector shaft 13 which operates the clutch (not shown) to start the rotation of the translator shaft 52, which operation, as can be seen, takes place during the receipt of the fourth signal element. This shaft 52 carries the transfer cam indicated in line "G", which operates to rock the frame 47 carrying the storage members 25 to transfer the stored signal combination to the bell cranks 49 engaging the five vertical rods 50, known as code bars which form the first part of the translator mechanism, which transfer operation has been described above.

The transfer cam carried on shaft 52 operates approximately during the receipt of the stop element and immediately after the storage members 25 have set the code they are returned to their normal position whereupon said cam shown in line H operates to restore to their normal position any of the storage members which have been depressed.

It can be seen that part of the return traverse movement of the light frame 27 (line E) and the transfer from the storage members 25 to the code bars 50 (line G) and also the resetting to

normal of the storage members (line "H") can take place during the earlier part of the reception of the next ensuing signal combination.

This characteristic of the mechanism described enables the various separate operations to be carried out in relatively deliberate manner, and, taken in conjunction with the advantage obtained by only requiring the armature 2 to actuate parts of minimum moment of inertia, it permits of higher operating speeds in terms of letters-per-minute without any of the moving parts of the mechanism being subjected to particularly exacting conditions and thus more reliable operation is obtained.

What is claimed is:

A signal selector and storage mechanism for a printing telegraph receiver comprising a signal receiving electromagnet having a cooperating armature adapted to have two selective positions as determined by the successive code elements of a received signal, mechanical means for cyclically moving said armature from one of said positions to the other, said means operating independent of a received signal, a plurality of

storage members, one for each code element, each adapted to be set in response to a received signal code element, striking means, intermediate means disposed between said storage members and said striking means, said striking means adapted to selectively urge said intermediate means against said storage members under control of said mechanical means and said armature and means for traversing said intermediate means with respect to said storage members, said intermediate means adapted to act selectively upon said storage members in turn in response to received signal code elements.
